INVENTOR

Charles F. Copeland

UNITED STATES PATENT OFFICE.

CHARLES F. COPELAND, OF BOSTON, MASSACHUSETTS, ASSIGNOR TO THE
THERMO GAS CARBONIZER COMPANY, OF MAINE.

CARBURETOR.

SPECIFICATION forming part of Letters Patent No. 288,622, dated November 20, 1883.

Application filed May 17, 1883. (No model.)

To all whom it may concern:

Be it known that I, CHARLES F. COPELAND, of Boston, in the county of Suffolk and State of Massachusetts, have invented certain new and useful Improvements in Carburetors, of which the following is a specification.

My invention relates to that class of carburetors in which the carburetor-fluid drops onto a helicoid, and slowly flowing down the surface of the helicoid meets air and gas, which is sent in at the lower end of the cylinder, so as to traverse the said helicoid in an upward direction while the hydrocarbon liquid is flowing downward; and it consists in the combination of the evaporating device above described with a steam-heating device and the thermostat-regulator. I attain these objects by the mechanism illustrated in the accompanying drawings, in which—

20 Figure 1 is a vertical section of my invention. Fig. 2 is a horizontal section taken on line *x y* of Fig. 1. Fig. 3 is a vertical section enlarged, showing my automatic valve.

25 This invention is an improvement on the one granted to me March 20, 1883, No. 274,176.

A represents the cylinder inclosing my devices.

30 B' is a helicoid formed within the said cylinder, and so constructed that its periphery may form an air-tight joint with the interior of the cylinder.

N is the hydrocarbon-fluid-supply pipe.

35 The parts above referred to are fully described in the above-mentioned Letters Patent.

I will now proceed to describe the parts of this device which I consider as new.

P is an open steam-passage formed in the central part of the helicoid B' B'. This hollow passage P, Fig. 1, is supplied with steam 40 from the supply-pipe D.

E is a quill-valve. (Shown in detail in Fig. 3.) This quill-valve E has an opening, as shown, which is normally at the end of the steam-pipe D, so as to admit of the free passage 45 of steam from the pipe D to the central opening, P, of the helicoid B' B'. This quill-valve E has a valve-stem, E', which passes through the stuffing-box K K', and terminates in a square shank, E², said shank E² being embraced 50 by a boss, F, attached to the spiral thermostat L, so that any movement of the thermostat will cause a corresponding movement of the quill-valve E.

For convenience in adjusting the thermostat, I have a series of screws, M M M, either one of which may be used to clamp a particular portion of the thermostat L onto the bracket C.

55 The thermostat-coil consists of two strips of 60 metal, *a b*, of different expansibilities. I prefer brass and steel; but other metals may be used for this purpose.

I claim—

In a gas-carburetor, the combination of the 65 steam-pipe D, the helicoid B' B', said helicoid having a steam-space, P, the thermostat L, and quill-valve E, all arranged to operate together substantially as described, and for the purpose set forth.

CHARLES F. COPELAND.
